UNITED STATES PATENT OFFICE.

CLARK F. RIGBY, OF BUTLER, PENNSYLVANIA.

OIL-WELL VALVE.

1,323,379.

Specification of Letters Patent.

Patented Dec. 2, 1919.

Application filed May 23, 1919. Serial No. 299,359.

To all whom it may concern:

Be it known that I, CLARK F. RIGBY, a citizen of the United States and a resident of Butler, in the county of Butler and State of Pennsylvania, have made a new and useful Invention in Oil-Well Valves, of which the following is a specification.

The object of my invention is to increase the efficiency of pumps in oil or similar wells 10 and to facilitate the removal of the pumps or the tubing in which they work and any other equipment within the casing.

A familiar form of oil well construction is shown in the drawings forming part of this 15 specification and in which Figure 1 is a longitudinal section through a portion of an oil well equipped with my invention and Fig. 2 is an enlarged section through the valve, packing and adjacent parts shown in 20 Fig. 1 and comprising the subject of my invention.

A well casing 1 is sunk into solid rock below the lowest water strata and then a 25 casing extension 2, of smaller diameter than casing 1, is sunk from a point above the bottom of casing 1 to the bottom of the well and a sealed, sliding joint is provided between the casing and its extension. The sliding joint is here formed by a packing ring 3 of 30 leather or other flexible and compressible material, seated in a container 4 and supported from below by the tapered top face 5 of valve chamber 6.

The top of container 4 is bell-mouthed to 35 guide descending fishing tools and just below the top is an undercut shoulder 7 which is adapted to be engaged by a fishing tool to pull the container and packing ring out of the well. Near the lower end of container 40 is a circumferential groove 8 and seated therein is a spring ring 9 with its bottom face tapered to facilitate insertion into the valve chamber 6. When valve chamber 6 is being lowered into the well, container 4 may be assembled therewith as 45 shown and the expansion of the compressed ring 9 will offer sufficient friction to secure the parts together in their descent but will not materially resist efforts to pull container 50 4 away from valve chamber 6. If the container is withdrawn, the shoulder 10 will pull the packing ring 3 along and lip 11 will protect it from being torn by the well casing.

When the pump is operating, pressure of 55 the column of liquid above container 4 will

force packing ring 3 outwardly against the wall of the casing. The joint formed thereby makes it unnecessary to extend the casing 1 to the bottom of the well as it provides a seal between casing 1 and extension 60 2 which renders the pump operative because it prevents the back-flow of liquid between the casing and extension.

The top section 12 of the casing extension is externally threaded at 13 to accommodate 65 the internally threaded lower end of valve chamber 6. Above joint 13, valve chamber 6 is offset from the extension by the bevel shoulder 14 which is perforated by port holes 15 and forms a seat for the valve 16. 70 Valve 16 has the disk face 17 and an undercut shoulder 18, the latter adapted to be engaged by a fishing tool. When raised, the top rim 19 of valve 16 abuts the bottom rim 20 of container 4. Thus shoulder 14 and 75 rim 20 limit the relative movement of valve 16 in its chamber 6.

It will be understood by those familiar with the art that the point where the casing may stop and the extension only continue may be several hundred feet above the bottom of the well. Throughout this distance gas will frequently collect in the space 21 between the well bore 22 and the casing extension 2, acquiring pressure 80 85 which, unless relieved, forces gas into the pump at the well bottom with the oil and water and seriously interfering with the pump's operation.

By the construction shown and described 90 herein, the pressure of the collecting gas, when sufficiently great, lifts the valve from its seat which permits the gas to escape through port holes 15 into the oil and water at a point far above the pump and where 95 it flows with the liquid to the well discharge. When this pressure is relieved gravity will seat the valve again and the interior of the extension is sealed off from the bore and casing as before.

In the operation of the well, it may become necessary to remove the pump, casing extension or tools left therein or all of these items. The column of liquid in the well, exerting the pressure which seals the joint 105 at the packing, renders this removal difficult or impossible. By sliding a hollow fishing tool down the cable and engaging shoulder 18 on valve 16, the valve may be lifted from its seat which will permit the liquid above 110

the valve to descend through port holes 15 and thereby remove the pressure from packing ring 3. This removal of tons of weight from the well cable load dispenses with the 5 costly and often unsatisfactory operation of bailing the well.

I claim:—

1. The combination in a well, of a casing, a casing extension, a pump and a valve 10 controlling the passage of fluids between the interior and exterior of said extension and located at a point above the pump.

2. In a well, a well casing, a casing extension within said casing, a seal between 15 said casing and said extension, and means below said seal for rendering it ineffective.

3. In a well, a well casing, a casing extension, a compressible seal between said casing and said extension and operated by 20 the weight of the liquid in the well above said seal, and means below said seal adapted to permit the withdrawal of said liquid.

4. In a well, a well casing, a casing extension of less diameter than the well bore, 25 a seal between said casing and said extension, a recess in said extension below said seal, and a valve operating automatically in said recess to permit the passage of gas under pressure inwardly through the wall 30 of said extension.

5. In a well, a well casing, a casing extension, a pressure operated seal between said casing and extension and a valve below

said seal adapted to remove the pressure operating said seal.

6. In a well, a well casing, a casing extension, a compressible packing between said casing and said extension, a member adapted to retain and to compress said packing and to slide within said extension, and 40 means on said member for frictionally uniting said member and said extension.

7. In a well, a well casing, a casing extension of less diameter than said casing and having an enlarged upper end which forms 45 a valve seat and part of a valve chamber and provided with port holes in the seat portion, a valve disk adapted to enter said enlarged end and to seat so as to close said holes, and a member adapted to enter said 50 enlarged end and be secured in said end above said valve so as to form with said end a chamber limiting the movement of said disk.

8. In a well, a well casing, a casing extension provided with an annular, ported valve seat at its upper end, a hollow, valve disk adapted to enter said end and rest on said seat, and a hollow, disk confining member adapted to enter said end and to clutch 60 said extension so as to limit the movement of said disk from said seat.

In testimony whereof I have hereunto subscribed my hand this 12th day of May, 1919.

CLARK F. RIGBY.
